Joseph F. Pond,

UNITED STATES PATENT OFFICE.

JOSEPH F. POND, OF CLEVELAND, OHIO.

STEAM-ENGINE.

SPECIFICATION forming part of Letters Patent No. 286,482, dated October 9, 1883.

Application filed March 5, 1883. (No model.)

To all whom it may concern:

Be it known that I, JOSEPH F. POND, of Cleveland, in the county of Cuyahoga and State of Ohio, have invented new and useful 5 Improvements in Steam-Engines, of which the following is a specification.

My invention relates to steam engines; and the novelty consists in the construction, arrangement, and adaptation of parts, as will 10 be more fully hereinafter set forth, and specifically pointed out in the claims.

It is well known that there is a latent power or force in steam which is developed when the steam-atoms are broken or disintegrated. 15 This breaking up of the atoms has before been attempted by a separate force. I seek to accomplish the same end by the force of the steam itself.

In a steam-cylinder having ports upon a 20 single side the admitted steam first strikes the side of the cylinder and then reverberates. I seek to obviate this by having the currents of steam meet their first resistance at the center of the cylinder.

25 In steam-engines where but one steam-connection leads to the steam-chest only that amount of pressure can be obtained which the capacity of that connecting-pipe will allow. I provide two such connections, and consequently feed to the cylinder a greater amount of steam and pressure at the beginning of the stroke as the crank passes over the center.

The object, in general, of my invention is 30 to obtain an increase of steam force from a given amount of boiler-pressure.

In steam engineering I have found it desirable to give more pressure, and from opposite sides at the beginning of the stroke, as the crank passes over the center. Steam admitted 35 to a cylinder from opposite sides and meeting in the center produces a concussion, which operates upon the piston to effect great power at the beginning of the stroke. When a concussion is produced, a given amount of friction is obtained, which in every instance creates heat, thus producing in a degree superheated steam.

The invention contemplates developing the latent power of steam by liberating said power in the destruction or breaking up of the

steam-atoms by the force inherent in the steam itself.

It contemplates impacting the steam directly behind the piston-head and approximately in the center of the cylinder.

55 It contemplates forcing two oppositely-moving currents of steam together, in order to break up the steam-atoms and to give the greatest amount of pressure at the point of contact, which is in the center of the cylinder and behind the piston-head.

It contemplates arranging two steam-chests on opposite sides of the cylinder, said chests receiving equal pressures of steam from the boiler, and each having port-connections with 65 the cylinder in the same transverse plane, whereby the valves, which operate simultaneously to disclose either pair of ports, will admit the steam into the cylinder in opposite directions. Said currents of steam, meeting, 70 as aforesaid, will increase the steam-pressure within the cylinder to a point greater than the pressure in either of the chests or within the boiler.

75 It also contemplates means whereby the piston is held in the center of the cylinder, and unequal friction, by reason of the piston being forced toward one side of the cylinder by the action of the steam entering either wholly or a preponderance thereof from one side of the 80 cylinder, is prevented.

To these ends the invention consists in the mechanisms fully illustrated in the accompanying drawings, which form a part of this specification, and in which—

85 Figure 1 is an elevation taken at right angles to the plane of the main shaft, and Fig. 2 a central vertical section.

Referring to the drawings, in which similar letters of reference indicate like parts in both 90 the figures, A designates the cylinder, mounted upon the frame B, and C is the piston-head, mounted upon the stem c. This stem is properly connected by cranks (not shown) to the shaft S, to which, by eccentrics or cams 95 and straps I and I', are connected the valve-roads h h' of the valves H H'.

The cylinder A is provided with steam-ports D D' E E', and the valves H H' operate in steam-chests G G', arranged on opposite sides 100

of the cylinder. Separate pipes *g* and *g'* connect the steam-chests with the boiler, and separate exhausts *R* connect the cylinder with a main exhaust, *Q*. The cylinder *A* is provided 5 with exhausts *F* and *F'*.

Now, it will be observed that the valves *H* and *H'* move simultaneously, and that each steam-chest receives its steam direct from the boiler. As the valves move together in either 10 direction, one pair of steam-ports *D D'* is uncovered, and the steam, at equal pressure, rushes in opposite directions through said ports, the currents meeting in the center of the cylinder, directly behind the piston-head, holding the piston in the center of the cylinder, 15 the concussion caused by the contact of the two currents breaking up the steam-atoms and liberating the latent force therein, the steam impacting behind the piston-head and in the center of the cylinder, thus obtaining at this 20 objective point a pressure at the moment of contact greater than that in either of the chests or in the boiler.

Having thus fully described the invention, 25 what I claim as new is—

1. An engine-cylinder having only two inlet-ports located at diametrically-opposite

sides of the cylinder, and provided with suitable valves for controlling said ports simultaneously, whereby the steam is conducted to 30 the center of the cylinder from two opposite sides, substantially as herein described.

2. An engine-cylinder provided with two separate steam-chests located on diametrically-opposite sides of the cylinder, two steam-inlets and two exhaust-ports, and suitable valves for simultaneously controlling said ports, substantially as described.

3. An engine-cylinder having two inlet-ports and separate steam-chests located at diametrically-opposite sides of the cylinder, suitable valves simultaneously operated, and independent boiler-connections for each chest, substantially as herein shown and described.

4. An engine-cylinder having two ports and 45 steam-chests located at diametrically-opposite sides of the cylinder, suitable valves for controlling said ports, and separate boiler-connections provided with valves, substantially as and for the purpose specified.

JOSEPH F. POND.
